**THERMOSTATIC CHARGE FOR MOTOR SYSTEM
OF EXPANSION VALVE AND METHOD OF
CHARGING**

Edward F. Kounovsky, Webster Groves, and Harold T. Lange, Huntleigh Village, Mo., assignors to Sporlan Valve Company, Inc., St. Louis, Mo., a corporation of Missouri

Filed July 23, 1959, Ser. No. 829,098
4 Claims. (Cl. 73—368.2)

This invention relates generally to improvements in a sensing system for a thermostatic expansion valve, and more particularly to a new and improved charge for the motor system of such a valve and to an improved method of charging the system.

Heretofore there have been three basic types of thermostatic charges commonly used in the motor system of the thermostatic expansion valves. The first type is a "limited pressure charge" employing the same fluid as used in the refrigeration system. The second type is a "liquid charge" employing the same fluid as used in the refrigeration system. The third type is a "liquid cross-charge" consisting of a volatile liquid plus a superheated vapor.

The motor system for a thermostatic expansion valve is well known, such system consisting of a sensing bulb to be located at some point in the refrigeration system, a diaphragm or bellows with its housing usually connected on the valve casing, and connecting capillary tubing.

The above mentioned "limited pressure charge" consists of a limited charge of volatile liquid, such liquid being the same as the refrigerant employed in the refrigeration system. At normal operating temperatures a portion of the charge is saturated liquid and the balance of such charge exists as a saturated vapor. Above a predetermined temperature the entire charge is in a superheated vapor phase. This type of charge is described in U.S. Patent No. 1,971,695, issued August 28, 1934, to Clyde E. Ploeger.

An advantage of the "limited pressure charge" is that overloading of the compressor motor is prevented because the charge limits the evaporator pressure to a predetermined maximum value. This maximum evaporator pressure value is known as the limiting pressure. Because the danger of overloading the compressor motor is obviated when starting up equipment at high temperatures, following defrost, or during other occasional periods of high loading, the selection of the compressor motor may be based on normal operating loads and temperatures.

Another advantage realized by the use of the "limited pressure charge" is that it permits the use of a thermal ballast in the sensing bulb of the motor system of the thermostatic expansion valve in order to reduce hunting, all as described and disclosed in U.S. Patent No. 2,573,151, issued October 30, 1951, to Harold T. Lange, and in Reissue No. 23,706, issued September 1, 1953, to Harold T. Lange.

An inherent disadvantage of the "limited pressure charge" is its tendency to produce higher superheat of the refrigerant vapor leaving the evaporator as the evaporating temperature is reduced. This action results in a corresponding loss in the capacity of the refrigeration system. In such a refrigeration system, the limiting pressure, or in other words the maximum evaporator pressure determined by the motor system of the expansion valve at which the entire charge converts to a superheated vapor phase, is set somewhat above the normal operating range in order to provide as rapid a temperature pull-down as possible without overloading the compressor motor. Because of this setting of the limiting pressure and because of the increasing superheat characteristic,

2

there may occur a flood-back of liquid refrigerant to the compressor at some point during the pull-down period especially if the final superheat is required to be low. These problems are usually related to commercial or low temperature equipment.

The second type or "liquid charge" is also the same as the refrigerant used in the system. However, the volume of the powerhead consisting of diaphragm or bellows in its housing and the volume of the bulb, together with the amount of charge are so proportioned that the liquid-vapor interface is always in the sensing bulb regardless of the temperature of the powerhead. As a result, the point of control is always in the sensing bulb. This "liquid charge" is always in the saturated liquid-vapor phase.

15 The third type or "liquid cross-charge" consists of a volatile liquid that can be the same as that refrigerant used in the refrigerating system or such a liquid having a lower vapor pressure and a flatter pressure-temperature curve than that of the refrigerant in the refrigeration system, together with a superheated vapor (non-condensable gas) such as carbon dioxide, air, nitrogen and the like added to increase the total pressure in the powerhead. Similar to the straight "liquid charge," the "liquid cross-charge" is so designed that the temperature control is 20 basically at the sensing bulb. In other words, the volume of the powerhead, the volume of the bulb and the amount of charge are so proportioned that a liquid-vapor interface exists in the bulb at all times regardless of the temperature of the powerhead.

25 30 The "liquid cross-charge" overcomes two of the disadvantages of the "liquid" and "limited pressure" charges. Because of its flatter pressure-temperature curve, it is less responsive, pressure-wise to changes in bulb temperature. Consequently there is less tendency for the refrigerant expansion valve to overfeed and hence stability control is improved.

35 In addition, with the "liquid cross-charge" the changing superheat characteristic is reversed from that of the "liquid" or the "limited pressure" charges. For example, as the evaporating temperature is reduced, the superheat of the refrigerant vapor leaving the evaporator becomes progressively lower, thereby enabling more of the evaporator to be available for cooling action. As a result, there is no danger of flooding liquid back to the compressor 40 at the start of the refrigerating cycle. It is necessary only to establish a setting on the expansion valve which will provide for an adequate superheat at the minimum evaporator temperature for any given job application.

45 50 However, the "liquid cross-charge" provides only partial overload protection by its changing superheat characteristic. Normally this extent of protection is inadequate.

55 Heretofore in order to provide the complete load limiting protection afforded by the "limited pressure charge," it has been necessary to incorporate in the valve design, a mechanical pressure-limiting device. This type of pressure-limiting device consists of a collapsing member such as a diaphragm or bellows, which is responsive to increasing evaporator pressure above a pre-set maximum limit and acts to throttle the expansion valve above such maximum value. While a mechanical pressure-limiting device is effective in providing motor overload protection, it is expensive and has various limitations as to size and range of pressures.

60 65 70 It is a primary object of this invention to provide a thermostatic charge for the motor unit of a refrigerant expansion valve that has the controlled stability and favorable superheat control characteristic offered by the flat-temperature curve of the "liquid cross-charge"; which operates with the simplicity of the "limited pressure charge" in providing complete compressor motor protection during periods of overload, and which enables

additional control stability by the selective use of a thermal ballast to reduce hunting as disclosed in Lange U.S. Patent No. 2,573,151 and Lange Reissue No. 23,706.

Another important object is to provide a thermostatic charge for a motor system which comprises a limited pressure charge of volatile liquid and the vapor of the liquid, and a gas which is non-condensable within the temperature and pressure ranges to which the motor system is subjected during use, such a charge providing the results and functional advantages mentioned previously.

Still another important object of the invention is to provide a method of charging the motor system of the thermostatic expansion valve with the thermostatic charge.

The foregoing and numerous other objects of the invention will more clearly appear from the following detailed description of the thermostatic charge together with the method of charging the motor system, particularly when considered in connection with the accompanying drawing, in which:

FIG. 1 is a graph of pressure-temperature curves for saturated refrigerant-500 and for a "limited pressure charge" of refrigerant-12;

FIG. 2 is a graph illustrating a calculated curve and an actual test curve of a "limited pressure cross-charge," and illustrating the limiting pressure of each curve, and

FIG. 3 is a graph of pressure-temperature curves for a "limited pressure cross-charge" showing the effect of varying amounts of air.

This invention relates to a thermostatic charge for a motor system of a thermostatic expansion valve which comprises a limited pressure charge of volatile liquid and the vapor of the liquid and a gas or a vapor that is superheated and non-condensable throughout the range of pressures and temperatures in which it is required to operate, such vapor and non-condensable gas raising the total pressure of the charge to a predetermined value selected to give a suitable limiting pressure at which the entire charge is in vapor phase. In this thermostatic charge the non-condensable gas is one that is chemically not reactive with the limited pressure charge.

According to ASHRAE Data Book, Design Volume, saturated liquid or liquid at saturation is the condition for co-existence in stable equilibrium of two or more distinct phases. For example, saturated liquid is liquid at boiling point or liquid which is not subcooled.

It is characteristic of all saturated liquids that those whose vapor pressures are lower than other such liquids at any given temperature also change less in pressure for a given temperature change. As for example, FIG. 1 of the drawing shows portions of the saturated pressure-temperature curve for two such saturated liquids between the temperatures of zero degree and plus 60 degrees F. The two saturated liquids are refrigerant-500, an azeotrope of dichlorodifluoromethane and difluoroethane, and refrigerant-12 also known as dichlorodifluoromethane or Freon-12.

From FIG. 1 it is apparent that the pressure rise for the refrigerant-12 charge is at a lower rate than that of refrigerant-500. With these two saturated liquids, it is seen that the pressure of refrigerant-12 at any given temperature is lower than the corresponding pressure of refrigerant-500. Moreover, it is seen that the curve for refrigerant-12 is flatter than the curve for refrigerant-500 which indicates a smaller pressure change for any given temperature change.

In addition, the relationship between the superheat and evaporating temperature is also indicated by the horizontal distance between the two curves, such as is indicated by line A-B, under the conditions where refrigerant-500 is employed as the system refrigerant and refrigerant-12 is employed as the thermostatic charge of the expansion valve. For example, at an evaporating temperature of 40 degrees F., the superheat is 10 degrees F. The point C

on the Freon-12 curve represents the limiting pressure value at which the entire charge is in vapor phase.

In a thermostatic expansion valve, the absolute pressure values differ because in addition to the evaporating pressure, a spring force is applied which opposes the pressure exerted upon the valve by the diaphragm of the motor system and tends to close such valve. Therefore, the pressure of the thermostatic charge in the motor system must be elevated accordingly. This action may be accomplished either by the provision of an opposing spring that assists the pressure of the thermostatic element and tends to open the valve or by the addition of a non-condensable gas in the thermostatic charge that raises the total pressure. The provision of a non-condensable gas in a thermostatic charge and the particular method involved in charging the thermostatic motor system represents the present inventive features.

One method of charging the thermostatic motor system, which consists of a sensing bulb, diaphragm or bellows with its housing and connecting capillary tubing, includes the step of evacuating the system. Then, a volatile fluid is introduced in vapor form by maintaining the temperature of the entire system above the saturation temperature corresponding to the charging pressure selected. Typical fluids that can be utilized in this last described step are isobutane, methylchloride, dichlorodifluoromethane (Freon-12), monochlorodifluoromethane (Freon-22), propane and the like. Following this last step, a non-condensable gas is introduced into the system to raise the total pressure of the thermostatic system to a predetermined value. The non-condensable gas that can be added may be air, carbon dioxide, nitrogen or any other gas which does not react chemically with the volatile fluid. The total pressure selected for the motor system charge is one which will give suitable limiting pressure at which the entire charge is in vapor phase, such as the limiting pressure value illustrated in FIG. 2.

After the introduction of the non-condensable gas, the system is closed and sealed.

As one example of the above described method, after the thermostatic system is evacuated, such system is charged with Freon-12 to a gauge pressure of 68 p.s.i. while the temperature is maintained at 90 degrees F. The saturation temperature of Freon-12 at this gauge pressure is 68 degrees F. Air is then added until the total pressure equals 83 p.s.i. gauge pressure and the system is closed and sealed. The saturation pressure for the volatile fluid at the charging temperature of 90 degrees F. is 99.8 p.s.i. gauge pressure.

Another method of charging the motor system of the refrigerant expansion valve is to reverse the above described procedure. In other words, after evacuation of the system, the air is introduced into the system first to a predetermined pressure value, as for example, to 15 p.s.i. absolute, and then the volatile fluid, such as Freon-12, is introduced into the system with the air to raise the final pressure to 83 p.s.i. gauge pressure.

Of course, in each of the above described methods, non-condensable gases other than air can be utilized effectively.

Still another method of charging the thermostatic system, if air is used as the non-condensable gas and if the air pressure is not to exceed one atmosphere, is to evacuate the system partially or not at all, as required and then the volatile fluid is introduced into the system in vapor form in the manner previously described to raise the total pressure to the predetermined value.

In the last two charging methods, the total pressure of the thermostatic system must be less than the pressure of saturated vapor for the volatile fluid used at the charging temperature selected.

Basically, the partial pressure of the non-condensable gas varies with temperature according to Charles's law, while the vapor pressure of the volatile liquid charge follows the pressure-temperature curve for saturated vapor

until the point of complete vaporization occurs, such as at the limiting pressure point C of FIG. 1. At temperatures above the point of complete vaporization, which occur at a limiting pressure value, the pressure of the thermostatic system follows Charles's and Dalton's laws. However, these pressure-temperature characteristics are further modified because of absorption of the non-condensable gas by the volatile liquid charge, or modified by the use of a thermal ballast in the sensing bulb.

It is well known that when a non-condensable gas is mixed with saturated liquid-vapor, absorption of a portion of the non-condensable gas by the liquid takes place. This absorption has been observed since 1934 in thermostatic expansion valves manufactured by Sporlan Valve Company of St. Louis, Missouri, assignee of the present application and invention.

One type of "liquid cross-charge" for a representative valve manufactured by Sporlan Valve Company, known as type "G" valve, consists of methyl chloride and air. In this particular valve, the internal bulb volume is 0.44 cubic inch, the internal volume of the diaphragm housing is 0.14 cubic inch and the internal volume of the connecting tubing is 0.09 cubic inch. The amount of liquid in the charge is sufficient to fill completely the diaphragm housing without completely depleting the bulb. In other words, in accordance with the prior disclosure, there is a liquid-vapor interface in the sensing bulb at all times.

It has long been noted that this type of charge (saturated vapor over liquid plus a non-condensable gas) produced a pressure that was proportional to the temperature of the bulb, the capillary tubing and the diaphragm housing. The pressure effect was a resultant of all three temperatures and directly related to the volume of all three parts of the thermostatic system. The relative volume of the tubing is small and has been neglected in the following tabulation of the above effect.

	1st System	2d System
Internal Bulb Volume (cu. in.)	0.44	1.4
Weight of Methal Chloride (grams)	5.45	5.45
Partial Pressure Air Change (p.s.i. absolute)	23.6	23.6
Bulb and Tubing Temperature (° F.)	80	80
Diaphragm Case Temperature (° F.)	80-32	80-32
Element Pressure (p.s.i. gauge)	90-75	94.5-83.0
Change in Element Pressure (p.s.i.)	15	11.5
	7	

From the above table, it is seen that in the first thermostatic system tested the internal bulb volume was 0.44 cubic inch while in the second thermostatic system the internal bulb volume was 1.4 cubic inches. In each of the systems tested, the weight of methyl chloride was 5.45 grams and the partial pressure air charge was 23.6 pounds per square inch absolute. In each system, the bulb and tubing temperature was maintained at 80 degrees F. while the diaphragm case temperature was varied from 32 degrees F. to 80 degrees F. In the first system, the element pressure varied from 75 p.s.i. gauge to 90 p.s.i. gauge for a pressure change of 15 p.s.i. In the second system, the element pressure varied from 90.5 p.s.i. gauge to 97.5 p.s.i. gauge for a change in element pressure of 7 p.s.i.

It has also been found, in a thermostatic system of the type described above in which the relative volumes of the bulb, the capillary tubing and the diaphragm housing affect the resultant pressure, that the amount of volatile liquid can be reduced to only a few drops with beneficial results. When such reduction in the amount of volatile liquid is made, there is an increased volume in the bulb available for vapor and gas mixture, and therefore the proportion of the volume of the bulb to that of the diaphragm case increases. Therefore, the pressure effect from bulb temperature predominates which is a desirable effect. This phenomenon is shown in the following table as test results.

	1st System	2d System	3d System
5 Weight of Methyl Chloride (grams)	5.45	1.8	0.2
Bulb Volume (cu. in.)	0.44	0.44	0.44
Partial Air Pressure (p.s.i. absolute)	23.6	23.6	23.6
Bulb and Tubing Temperature (° F.)	80	80	80
Diaphragm Case Temperature (° F.)	80-32	80-32	80-32
Element Pressure (p.s.i. gauge)	90-75	94.5-83.0	104.5-97.5
10 Change in Element Pressure (p.s.i.)	15	11.5	7

From the above table, it is seen that the thermostatic system had an internal bulb volume of 0.44 cubic inch, the partial air pressure charge was 23.6 p.s.i. absolute, and the bulb and tubing temperature was maintained at 80 degrees F. In each of the three tests of this system, the diaphragm case temperature was varied from 32 to 80 degrees F.

In the first test the weight of methyl chloride introduced 20 into the system as a charge was 5.45 grams. Upon varying of the diaphragm case temperature within the temperature range indicated, the element pressure varied from 75 p.s.i. gauge to 90 p.s.i. gauge, thus showing a change in element pressure of 15 p.s.i.

25 In the second test, the weight of methyl chloride charge was 1.8 grams. The element pressure varied from 83.0 p.s.i. gauge to 94.5 p.s.i. gauge, thus indicating a change in element pressure of 11.5 p.s.i.

In the third test, the system was charged with methyl 30 chloride having a weight of 0.2 gram. This particular charge represents one within the teaching of this invention. In other words it is a limited charge of volatile liquid and the vapor of the liquid with the addition of a superheated vapor such as air to increase the pressure.

35 At a predetermined pressure value, called the limiting pressure, the entire charge will be in vapor phase. In this test, the element pressure varied from 97.5 p.s.i. gauge to 104.5 p.s.i. gauge for a change in element pressure of 7.0 p.s.i.

40 It is believed that in any thermostatic system containing a non-condensable gas plus a volatile liquid and the vapor of the liquid, absorption of a portion of the non-condensable gas by the liquid and vapor occurs and that the volume of the component parts of the system and their temperatures effect the element pressure. The amount of such absorption varies with the temperature, pressure, the nature of the volatile liquid, and the non-condensable gas. This absorption causes a deviation from the theoretical pressures calculated according to Dalton's 45 law.

FIG. 2 of the drawing shows the comparison between a calculated curve and an actual test curve in which the bulb, tubing and diaphragm housing temperatures are varied together.

55 The thermostatic system for which the test was run and on which the calculations were based for the actual test curve in FIG. 2, was charged with Freon-12 added to air at one atmosphere to a total pressure of 83 p.s.i. gauge at 80 degrees F.

60 In addition, the amount of non-condensable gas affects the slope of the pressure-temperature curve. For example, increasing the amount of non-condensable gas results in a flattening of the curve. The curves illustrated in FIG. 3 of the drawing were plotted with the 65 same basic charge as that described above with respect to FIG. 2, except for varying amounts of air. These curves illustrate the effect of flattening the pressure-temperature curve upon increasing the amount of air.

70 The thermostatic charge from which the actual test curve shown in FIG. 2 was calculated is designed to produce a fairly extreme cross-charge effect when used on a refrigeration system employing refrigerant-500. If a less extreme effect should be desired, less air or a higher 75 pressure volatile liquid, or both, could be used. There-

7
fore, by the proper selection of charge components, various characteristics can be obtained for different refrigerants.

Although the invention has been described by making detailed reference to a single thermostatic charge and to a method of charging a thermostatic system, together with several modifications, such detail is to be understood in an instructive, rather than in any restrictive sense, many variants being possible within the scope of the claims hereunto appended.

We claim as our invention.

1. A charge for a motor system of a thermostatic expansion valve comprising a motor system, a limited pressure charge in said motor system of volatile liquid and the vapor of the liquid, and a gas which is non-condensable throughout the range of temperature and pressures to which the motor system is to be subjected during use, the non-condensable gas raising the total pressure of the charge to a predetermined value selected to give a suitable limiting pressure at which the entire charge is in vapor phase.

2. A charge for a motor system of a thermostatic expansion valve comprising a motor system, a limited pressure charge in said motor system of volatile liquid and the vapor of the liquid, and a vapor that is superheated and non-condensable throughout the range of pressure and temperature in which it is required to operate the last said superheated vapor raising the total pressure of the charge to a predetermined value selected to give a suitable limiting pressure at which the entire charge is in a superheated vapor phase.

3. A charge for a motor system of a thermostatic expansion valve adapted for use in a refrigeration unit

comprising a motor system, a limited pressure charge in the motor system of volatile liquid and the vapor of the liquid, and a non-condensable gas that is chemically unreactive with the limited pressure charge which is non-condensable throughout the range of temperatures and pressures to which the motor system is to be subjected during use and which raises the total pressure to a predetermined value selected to give a suitable limiting pressure at which the entire charge is in a superheated vapor phase.

10 4. In a thermostatic expansion valve adapted for use in a refrigeration unit, a motor system including a sensing bulb, a flexible motor element with its housing and connecting capillary tubing, and a charge in said motor system comprising a limited pressure charge of volatile liquid and the vapor of the liquid and a gas which is non-condensable throughout the range of temperatures and pressures to which the motor system is subjected during use the vapor of the liquid and the non-condensable gas raising the total pressure of the charge to a predetermined value selected to give a suitable limiting pressure at which the entire charge is in superheated vapor phase in response to bulb temperature.
